UNITED STATES PATENT OFFICE.

ANDREW GEO. COUCH, OF EASTPOINT, GEORGIA, ASSIGNOR TO THE COUCH BROTHERS & J. J. EAGAN COMPANY, OF SAME PLACE.

HORSE-COLLAR.

SPECIFICATION forming part of Letters Patent No. 672,976, dated April 30, 1901.

Application filed June 2, 1900. Serial No. 18,893. (No model.)

To all whom it may concern:

Be it known that I, ANDREW GEO. COUCH, a citizen of the United States, residing at Eastpoint, in the county of Fulton and State 5 of Georgia, have invented certain new and useful Improvements in the Manufacture of Horse-Collars, of which the following is a specification.

My invention relates to the manufacture 10 of horse-collars, and especially to the character of casings and the mode of making the same from a single strip of material without cutting or gores and of the desired curved form, as fully set forth hereinafter and as 15 illustrated in the accompanying drawings, in which—

Figure 1 is a perspective view showing one section of a horse-collar made from my improved casing. Fig. 2 is a view showing the 20 manner in which a single strip is folded, formed, and united at the edges in the manufacture of the casing. Fig. 3 is a view showing the following step or process of manufacture. Fig. 4 is a view illustrating the position 25 of the parts after the outer folds and other portions of the strip have been sewed by a seam passing through the edge of the outer fold. Fig. 5 is a section on the line 5 5, Fig. 4, before the casing has been turned. Fig. 30 6 is a section showing the position of the parts after the casing has been turned inside out. Fig. 7 is a view in section of the parts after being stuffed.

The two casings A of the collar are alike, 35 and each consists of a single piece of fabric folded upon itself, so as to form the straight folded edge 1, and rounded near one end and contracted toward the other, as shown. The overlying edges of this piece are sewed together along the line x, extending from the contracted end to and partly along the rounded end, as shown in Fig. 2. The upper portion of the strip thus folded and sewed is then drawn toward the stitching x, so as to carry 40 the line of fold from the line 1, Fig. 2, to the position of the line 2, Fig. 2, thus forming a fold 3 of the surplus material, and the strip is then basted along the line y, Fig. 3, and the fold 3 is laid with its edge upon this basted 45 line, and a line of stitches v is then run through the fold 3, adjacent to the edge there-

of, and through the underlying parts of the material, following the basted line y. By thus forming the fold 3 and stitching it along the line y, as described, there is also formed a 55 fold 4 of substantially uniform width, the line of stitching v being parallel to the edge of the fold 4 and passing through the fold 3 near the edge and through the material beneath, as shown in Fig. 5. As the lower portion of the strip is curved and as it is desired to impart a like curve to the fold 4, this result is secured by puckering the fold of the edge 3, as indicated in Figs. 3 and 4. After these operations the bag or casing thus formed is 60 turned inside out, thus bringing the fold 4 to the outside and carrying to the inside that portion forming an infold 5 of the casing between the straight edge 2 and the line of stitching v, and the seam x is also carried inside of the casing, as shown in Fig. 6. By this means a casing is formed consisting of two parts A B, the part A being the largest, contracted at each end and greatest in diameter at a point above the lower end, while the 70 part B is of substantially uniform diameter. These two parts are now suitably stuffed with hair, moss, or other suitable material, so as to form two connected cushions, the cushion B being cylindrical and of substantially uniform diameter and the cushion A being largest near the lower end, but contracted at both ends, as required in a section of the horse-collar.

In the act of stuffing the part A of the casing the infolded portion 5 will be forced down against the inner side of the outer portion of the casing, and will thus present a greater thickness at the point in the collar which the hames bear upon, so that if the outer part of 80 the casing should wear away the integrity of the casing is still retained and the packing is not exposed.

It will be seen that by the method of manufacture above set forth the casing is made of 95 a single piece of fabric, not only avoiding the waste which comes from cutting the separate sections of different shape and the necessity of sewing them together, but also avoiding the weakness resulting from seams, injury 100 from ripping, and insuring much greater durability.

The puckering of the fold 3 is an important feature in connection with this mode of manufacture, as by this means it is possible to impart any desired contour to the cushion-piece A, and yet preserve the uniform diameter of the bearing-roll B, and gives to the latter the desired curve and set, so that it is maintained in a position to prevent the hames from leaving the collar in backing or in holding back in going down hills.

Two casings of reverse curvatures stuffed as above described may be connected together either at the bottom or the top.

The strip from which the casing is made 15 may be of canvas or any other suitable material, and the casing may be protected from wear by overlays of leather, as required, at any desired points.

While I have referred to the line of bast-
20 ing y and while this serves to retain the parts of the strip in position after drawing up the fold 3, it is not absolutely necessary to use the same, and the proper line upon which to lay and sew the fold 3 may be indicated by
25 pencil-line.

Without limiting myself to the precise steps or form and arrangement shown and described, I claim as my invention—

1. A casing for a section of a horse-collar
30 consisting of a single strip of material folded upon itself and inturned and united at the edges, divided by a curved line of stitching

v , into two unequal parts A, B, the part A of varying width, the material being puckered adjacent to the lower portion of the line v and to the widest portion of the part A, to impart a curved form to the casing when stuffed, substantially as set forth. 35

2. A casing for a section of a horse-collar consisting of a single strip of material folded 40 upon itself and united by stitching at the edges along the line x , and at v , forming a larger portion A tapering toward the ends and a smaller cylindrical portion, and having an infolded portion within the portion A; the 45 line of stitching at v , passing through the base of the infold and through the adjacent portions of the casing, substantially as set forth.

3. A horse-collar provided with casings each 50 consisting of a single strip of material folded upon itself and united at the edges and having an infold 5 and a securing-seam v , the infold 5 lying against that portion of the casing subject to the wear of the hame, substantially 55 as set forth.

In testimony whereof I have signed my name to this specification in the presence of two subscribing witnesses.

ANDREW GEO. COUCH.
